UNITED STATES PATENT OFFICE.

SPENCER W. MCKELLIP, OF PHILADELPHIA, PENNSYLVANIA, ASSIGNOR TO WIRT COMPANY, OF GERMANTOWN, PENNSYLVANIA, A CORPORATION OF MAINE.

ADJUSTABLE ELECTROMAGNETIC UNIT.

Application filed April 8, 1926. Serial No. 100,662.

My invention in its broad aspects relates to a novel construction of an adjustable electro-magnetic loud speaking telephone unit and also to simple and effective means for controlling, stabilizing, and manually adjusting or moving the armature or vibratory member of said unit without hindering or dampening the vibrations thereof.

My novel device comprises a base of substantially non-vibratory material composed in part of non-magnetic material or insulating material, such as moulded hard rubber or similar material upon which are mounted the various parts of the unit, whereby the vibration set up in the vibratory members of the unit tend to be confined or limited to said base member and are not absorbed or transferred to parts of the unit, which are not intended to vibrate, said base having mounted thereon the two coil supports, in the center of, or between which, is the electromagnetic coil having a hollow core.

The permanent magnet, used to create a magnetic field is clamped to the two coil supports, and the four pole pieces are attached to the sides of the coil supports in such a manner that when the milled ends of said pole pieces overlay one another with a gap in between, all four are the direct magnetic reverse of one another in both horizontal and vertical planes.

My invention further consists of a vibrating member or armature fixedly supported at its inner or bottom end but free to vibrate at its upper end, said armature being held in its proper position between thin plates carried by a screw passing through a tubular post or spacer and supported from the hard rubber base aforesaid. The post or spacer is so positioned as to permit the outer or free end of the armature to pass through the gap between the four pole pieces.

My invention further consists of a simple and direct means, whereby the vibrations set up in the armature or main vibratory member of said unit are directly transferred or carried to a tympanum, diaphragm, cone or other suitable sound regenerating or sound reproducing member, to produce sound waves, by a light spring wire, or reed, attached directly to the armature itself, and extending therefrom in opposite directions to said sound reproducing member and to suitable adjusting devices respectively.

In a unit of this general character aforesaid which creates a double push and pull action on the armature, due to the reverse position of the pole pieces, the strongest vibrations can be obtained where a permanent magnet is used, and when the armature is placed directly in this powerful magnetic field, as is the case in my novel unit, there is naturally a decided tendency for the armature to be deflected or drawn to either one side or the other. Of course if the armature is allowed to hit or contact with one of the pole pieces the rate of its vibratory efficiency is impaired, and in order to create the best effects it is desirable for the armature to float in the gap between the poles, or in other words, to be in proper magnetic balance between said poles. If the armature is constructed of material thick enough so that it has enough rigidity within itself to overcome the magnetic pull either one way or the other and hold a magnetic balance itself, I have found that the vibrations are not of the same intensity at various frequencies and also that the vibrations over the entire range of frequencies are materially cut down or reduced, which, when the unit is connected to a suitable tympanum, diaphragm, cone or the like would have a tendency to deteriorate or cut down the volume of sound produced by such an organization.

In other words I find that to produce a maximum amount of vibration with a given amount of pulsating electrical energy being fed through or impressed upon the electromagnetic coil, that the armature should be preferably constructed of light, soft, iron held in its proper position or in magnetic balance between the poles of said unit and further that the method or means employed for holding the armature between said poles should still allow the armature to vibrate freely and not have a dampening effect thereon. My novel construction not only accomplishes the foregoing ends but also further allows or provides for a manual adjustment or moving of the armature in the gap between the poles.

To the above ends my invention consists of a novel manner of mounting and adjusting the armature in a unit of this character, said armature having its inner end fixedly supported with its outer end free to vibrate, and having a reed passing therethrough and brazed thereto, said reed having one end

connected to a sound regenerating or reproducing device and its other end fixedly secured to a resilient stabilizing or adjusting bar, capable of being manually adjusted, 5 there being stops provided to limit the extent of said manual adjustment.

It further consists of a novel manner of mounting and supporting the armature and the armature adjusting mechanism, and a 10 novel manner of mounting and collocating the coil, the permanent magnet and their adjuncts.

It further consists of a novel manner of collocating the reed and armature, and a 15 novel means for effecting the simultaneous adjustment of both said reed and armature.

It further consists of other novel features of construction and advantage, as will be hereinafter pointed out in the specification 20 and claims appended hereto.

For the purpose of illustrating my invention I have shown in the accompanying drawings the form thereof which is at present preferred by me, since the same has been 25 found in practice to give satisfactory and reliable results, although it is to be understood that the various instrumentalities of which my invention consists can be variously arranged and organized and that my invention is not limited to the precise arrangement and organization of the instrumentalities as herein shown and described.

Figure 1, is a vertical sectional view of 30 an adjustable electro-magnetic unit embodying my invention the section being taken on line 1—1 Figure 2, certain of the parts being shown in elevation.

Figure 2, is a plan view of the device.

Figure 3, is a rear elevation of the device.

Figure 4, is an enlarged view similar to 40 Fig. 1 showing the coil in section.

Figure 5, is a perspective view showing the manner of connecting the reed with the armature and its adjuncts, and my novel adjusting mechanism therefor, certain parts being omitted for clearness of illustration.

Similar numerals of reference indicate corresponding parts.

My novel adjustable electro-magnetic unit indicated generally by 1 is connected by 50 means of a binding screw 30 to a loud speaker or acoustic device indicated by 2, and comprises the coil 3 having the armature or vibratory member 4 passing therethrough 55 which is attached to the member 2 by a connecting element such as a pin or reed 5, said reed and armature being brazed together or otherwise rigidly connected at the point 6 so as to form a unitary structure, as will be 60 understood from Figures 4 and 5.

7 designates the coil supports of iron or steel carrying the pole pieces 8, and to which is attached the base 9 of suitable insulating material, as hard rubber or the like, 65 or it may be made of brass or other non-

magnetic material, 10 is the permanent or horse shoe magnet which is supported by the magnet clamp 11. 12 designates the spacing sleeve surrounding the bolt or armature support 18, 13 the terminal block, and 14 the unit 70 support by which it may be connected to a suitable base or standard not shown.

The reed 5 passes through the hole 16 in the base 9, into engagement with the upper or free end of the resilient, stabilizing control and adjusting bar 17, to which it is rigidly secured. The lower end of the bar 17 is locked or held permanently as will be hereinafter explained, and as best seen in Figures 4 and 5.

18 designates a bolt which passes through the lower end of the armature 4 which latter has the thin plates 19 on each side thereof, said bolt passing through the spacing sleeve 12 above referred to. The upper ends of the plates 19 are extended upwardly a short distance in proximity to the armature as indicated at 20, (see Figures 4 and 5), which construction has a stabilizing effect on the armature 4, one of said plates 19 being held between the head of said bolt and the lower end of said armature while the other of said plates is held between the opposite wall of said armature and the contiguous end of the spacing sleeve 12. The bolt 18 after passing through the sleeve or spacing member 12, passes through the washer 29 and base 9, and has on its outer end the washer 21 and the inner lock nut 22, the outer end of said bolt 18 passing through the lower end of the bar 17, which latter is locked or secured in position thereon by the outer lock nut 23.

By tightening the nut 23 which has a flat surface next to the resilient, stabilizing, control and adjusting bar 17, the lower end of the latter is rigidly and immovably held in fixed position, while the upper end thereof is capable of being flexed or adjusted to a slight extent, as will be hereinafter explained.

The adjusting screw 24 which is threaded into the base 9 has the manually operable knob 25 on the outer end thereof, and passes freely through a hole in the bar 17, but the latter is locked with respect to said adjusting screw by the inner and outer lock nuts 26 which are tightened against the bar 17 so that when the latter is rotated in the base 9, there is a slight but adequate lateral movement imparted to the upper end of the bar 17, so that the armature 4 is simultaneously adjusted to position it centrally between the pole pieces. Carried on the screw 24 is a pointer or finger 27, the movement of which in either direction is limited by the nuts 28 of the clamping bolts, common to the members 9 and 14, whereby said finger 27 acts as a stop to limit the extreme movement in either direction of the armature 4 and bar 17, beyond the approximate desired position

of the armature 4 with respect to the gap between the pole pieces 8.

The armature 4 is helped in maintaining its magnetic balance by the two thin leaves 5 19 on opposite sides of its lower end, and the whole armature assembly consisting of the thin plates 19, armature 4, tubular post or spacer 12 and the washers 29 and 21 are locked or held to the base 9 by the screw or bolt 18, which passes through all said members including the base and is drawn tight and held in place by the lock nut 22. This screw 18 is made sufficiently long to also pass through the thin bar 17 which is made 10 of spring brass, bronze or other suitable material and is placed directly between the lock nuts 22 and 23.

The reed or connecting member 5 which I use to transmit the vibrations from the armature to a diaphragm or acoustic member 2, to produce sound waves, is preferably attached to the armature 4, adjacent the lower pair of the pole pieces at the bottom of coil 3 so that a considerable movement is imparted to said reed which results in a maximum intensity of vibrations being transmitted through the reed to the diaphragm.

The armature 4 is held fixed at its inner end, and vibrates in the gap between the 30 poles 8 and the reed being brazed directly as at 6 in a position at right angles to the armature, it will be apparent that when the armature 4 moves from side to side, the reed will not only have a longitudinal movement, but 35 a slight up and down movement at its point of attachment. This vertical movement, though slight, is augmented at the free end of the reed or pin, the amount of amplification of movement of course depending upon 40 the length of the pin and its rigidity. The outer end of the pin is attached to the acoustic element 2, and in order therefore to prevent the latter from dampening or retarding the movement of the armature and to transmit 45 from the armature to said elements all the armature vibrations I use a light springy reed 5 which will flex to a certain extent and will allow the armature 4 to vibrate freely.

I have found from extensive experiments 50 that it is essential in transmitting this maximum vibration to the diaphragm 2 that the vibrations set up in the armature 4 be carried in as direct a manner as is possible to said diaphragm. There should be nothing 55 to interfere with this transmission of vibration, which is effected by my novel construction, since the reed 5 while fastened to or brazed to the armature 4 also passes through the latter, also through the opening 16 is the base 9 and terminates or is fastened to the front end of the thin springy bar 17 which is fastened to and against the armature assembly by the lock nut 23 on the end of the bolt 18. By this formation I produce a 60 light, rectangular, continuous, vibratory

assembly, wherein the armature 4 and the upper end of the bar 17 form two parallel sides of the rectangle and the connecting end or extension 31 of the reed, the tubular post 12 and the inner end of the screw 24 form 70 the other two parallel sides. The threaded stem 24 passes through the center of the resilient bar 17 at a point approximately half way between the junction of the reed therewith and the inner end positioned between the lock nuts 22 and 23 and can be rotated freely to a limited extent. The front end of the stem 24 being threaded into the rubber base 9 of the unit, it will be seen that when said stem is turned in either direction the bar 17 is moved laterally and the armature 4 is likewise moved, due to the reed 5 connecting therewith. The bar 17 is of resilient, vibratory metal of the proper width and thickness, so that it will along 80 with the stabilizing plates 19 at the fixed end of the armature 4 assist the latter in maintaining a state of magnetic balance and in case of a blow on the diaphragm or if for any other reason the armature should contact with a pole piece 8, it can be manually moved by the knob 25 back to the proper position as seen in Figs. 1, 2, 4 and 5 and practically held in a point of magnetic balance without materially affecting the intensity of vibration. 90

It will be apparent from the foregoing that my novel unit will produce for and transmit to a desired sound reproducing tympanum or diaphragm of any description, the maximum amount of vibration with the least amount of loss, and I have further provided a novel means of stabilizing and manually adjusting the armature of said unit, so that the stabilizing and manual adjustment will not interfere with or dampen the generation or transmission of said vibrations. 100

It will be evident that if desired the adjusting and transmitting mechanism can be 110 positioned within the cone 2 for the sake of compactness, without departing from the spirit of my invention.

It will be evident that my novel device can be cheaply manufactured, since nearly all 115 the elements can be cut to the desired lengths from small rods, bars, tubes and the like, and readily and expeditiously assembled.

Having thus described my invention, what I claim as new and desire to secure by Letters Patent, is:

1. In a device of the character stated, a coil, an armature therefor passing through said coil and having its inner end fixedly supported, a reed secured directly to said armature passing therethrough and movable in unison therewith, a resilient bar attached to said reed and an adjusting device for said bar. 125
2. In a device of the character stated, the

combination of a coil, upper and lower pole pieces therefor, an armature passing through said coil and fixed at one end but free to vibrate at the other end, a flexible bar parallel to said armature and connected thereto and means for adjusting said bar and armature in unison.

3. The combination of a coil, upper and lower pole pieces therefor, an armature passing through said coil and between said pole pieces, a fixed support for one end of said armature, the other end of said armature being free to vibrate, a flexible bar parallel to said armature, and a reed having one end leading to a sound reproducer and its opposite portions fast to said armature and to said bar.

4. The combination of a coil, upper and lower pole pieces therefor, an armature passing through said coil and between said pole pieces, a fixed support for one end of said armature, the other end of said armature being free to vibrate, a flexible bar parallel to said armature and a reed having one end leading to a sound reproducer and its opposite portions fast to said armature and to said bar, and means for adjusting said bar and armature in unison.

5. The combination of a coil, upper and lower pole pieces therefor, an armature passing through said coil and between said pole pieces, a fixed support for one end of said armature, the other end thereof being free to vibrate, a flexible bar parallel to said armature, and a reed having one end leading to a sound reproducer and its other end fast to said armature and to said bar, and means for adjusting said bar, armature and reed in unison.

40 6. The combination of an insulating base, a coil, an armature fixed at one end thereof, a reed passing through said armature and fast thereto and having one end adapted to be connected to a sound reproducing element, a resilient bar to which the other end of said reed is connected, an adjusting screw passing through said plate and threaded into said base whereby said reed and armature are simultaneously adjustable and means for limiting the movement of said adjusting device.

55 7. In a device of the character stated, the combination of an insulating base, a coil, upper and lower pole pieces therefor, an armature passing through said coil and fixed at one end but free to vibrate at the other end, a flexible bar parallel to said armature and connected thereto, a reed fast to said armature and bar, an adjusting screw threaded into said base for adjusting said bar and armature in unison, and a bolt passing through the lower end of said armature, and said bar and base.

8. The combination of a base, a coil, upper and lower pole pieces therefor, an armature

ture passing through said coil and between said pole pieces, a bolt passing through the lower end of said armature, the other end of said armature, being free to vibrate, a flexible bar parallel to said armature, and having its lower end carried by said bolt, a reed having one end leading to a sound reproducer and its opposite portions fast to said armature and to said bar, and an adjusting screw threaded into said base and passing through said flexible bar and being fast thereto.

9. The combination of a base, a coil, upper and lower pole pieces therefor, an armature passing through said coil and between said pole pieces, a bolt passing through the lower end of said armature, the other end of said armature being free to vibrate, a flexible bar parallel to said armature and supported on said bolt, a reed having one end leading to a sound reproducer and its opposite portions fast to said armature and a spacing sleeve intermediate said armature and base.

10. In a device of the character described, the combination with a supporting frame, an electro-magnetic coil thereon having a pole piece and an armature having a free end adjacent the pole piece and its opposite end attached to the frame, of a stabilizer attached to the frame having a free end extending parallel to and in spaced relation to the free end of the armature, a rigid connection between the stabilizer and armature at a distance away from their attached ends, and a vibration transmitting member attached to said armature.

11. In a device of the character described, the combination with a frame, an electro-magnetic coil mounted thereon having a pole piece and an armature attached to the frame at one side of the coil and having its free end extending into juxtaposition with the pole piece, of a stabilizing vibratory member rigidly attached to the frame and having its free end extending in parallelism with the armature, a rigid connection between the vibratory parts of the armature and stabilizing member, means for adjusting the latter to vary the position of the armature with reference to the pole pieces, and a vibration transmitting member attached to the armature.

12. In a device of the character described, the combination with a vibratory armature and stabilizer spaced apart and each rigidly supported at one end, and a rigid connection between them at a distance from their attached ends, of a frame supporting said elements, means cooperating with the frame and stabilizing member for moving its free end and the free end of the armature laterally, a pole piece on the frame cooperating with the armature and a vibration transmitting member attached to the armature.

13. In a device of the character described, the combination with a permanent magnet having parallel extremities spaced apart, a frame embracing said extremities comprising spaced pairs of pole pieces extending towards each other from each of the extremities of the permanent magnet, the pole pieces of one polarity overlapping those of the other polarity, and also spaced therefrom, of an electro-magnetic coil located in the space between the overlapping ends of the pairs of pole pieces and having an aperture therein and an armature having one end fixedly secured at a distance away from said pole pieces and having its vibrating end 15 portion extending between each spaced pair of pole pieces.

In testimony whereof, I have hereunto signed my name.

SPENCER W. McKELLIP.
